UNITED STATES PATENT OFFICE.

CHALMERS SIMMS BROWN, OF LIMA, OHIO, ASSIGNOR TO BROWN AND BROWN, INC., OF LIMA, OHIO, A CORPORATION OF OHIO.

LOCKING MANHOLE COVER.

Application filed September 26, 1927. Serial No. 222,148.

This invention relates to locking manhole covers.

An important object of the invention is to provide a manhole cover having simple and novel locking means for retaining it in position, the locking means being readily releasable to permit the cover to be removed upon application of a proper implement.

A further object is to provide a manhole cover having a pivoted locking element and an operating member therefor adapted to retain the locking member in operative position by gravity and adapted to be moved by the insertion of a proper implement through an opening in the manhole cover for swinging the locking element to inoperative position.

A further object is to provide a manhole cover having a locking member arranged therebeneath and pivoted at its lower end to engage beneath a shoulder formed on the manhole frame, and to provide a locking element pivotally supported upon a pivot pin beneath the manhole cover and adapted to operate the pivoted lock, the latter element being provided with a cutout portion through which the pivot pin referred to extends to limit the movement of the locking member to operative and inoperative positions.

A further object is to provide a locking manhole cover adapted for use in connection with a manhole frame having an internal annular flange forming a shoulder for supporting the manhole cover, the latter being provided at one side with a stationary locking member adapted to be arranged beneath the annular flange of the frame and at its opposite side with a pivoted locking member also adapted to engage the annular flange.

Other objects and advantages of the invention will be apparent during the course of the following description.

In the drawings I have shown one embodiment of my invention. In this showing,

Figure 1 is a plan view,

Figure 2 is a section on line 2—2 of Figure 1,

Figure 3 is a detail section on line 3—3 of Figure 2, and

Figure 4 is a detail perspective of the locking element.

Referring to the drawings, the numeral 10 designates a manhole frame having the usual annular flange 11 at its lower end. The frame is provided with an open top and an internal

annular flange 12 is formed integral with the frame and projects inwardly thereof a short distance beneath the top of the frame.

A manhole cover 13 is adapted to be arranged in the open end of the manhole cover 10 and is supported upon the flange 12. This cover may be provided with the usual depressions 14 in its upper surface and is suitably braced by preferably integral lower webs 15. At one side, the manhole cover is provided with a pair of depending arms 16, the lower ends of which project outwardly beneath the flange 12 and are connected by a transverse pin 17. The arms 16 and pin 17 are preferably formed integral with the cover, as shown.

At its opposite side, the cover is provided with a pair of depending arms 18, the lower ends of which are connected by a pivot pin 19. A locking member indicated as a whole by the numeral 20 is arranged between the arms 18 and is provided at its lower end with a hub 21 having an opening through which the pin 19 extends. The locking member includes a pair of upstanding arms 22 having curved upper ends each provided with arcuate cutout portions 23 forming shoulders 24 at the ends thereof. The arms 22 are connected by a pin 25 secured thereto, as indicated in Figures 2 and 4.

A second pivot pin 26 is connected between the upper portions of the arms 18, and an operating lever 27 is mounted upon this pin. The operating lever extends between the arms 22 of the locking member and is provided with a down-turned portion 28 having a slot 29 formed therein to receive the pin 25. The operating member 27 is provided with an arm 30 extending inwardly a suitable distance from the pivot pin 26, and this arm is adapted to be engaged by a suitable hooked implement (not shown) which is adapted to be inserted through an opening 31 formed in the cover 13.

The operation of the device is as follows:

It will be noted that when the operating parts are in the position shown in Figure 2, the outer edge of the locking member is inclined downwardly and inwardly. In placing the cover in position, the pin 17 is first inserted beneath the annular flange 12, whereupon the opposite side of the cover may be dropped into position. The inclined edge of the locking member will contact with the annular flange to be moved inwardly,

thus permitting the cover to drop downwardly upon the flange 12 to be supported thereby. As soon as the cover is in normal position the weight of the arm 30 will swing 5 this portion of the operating member 27 downwardly, the opposite end of the operating member swinging outwardly carrying with it the pin 25, thus moving the locking member 20 to the position shown in Figure 10 2 with the outer portions of the upper edges of the arms 22 arranged beneath the flange 12. Thus it will be apparent that the cover will be secured in operative position. In order to remove the cover, a suitable hooked 15 implement of the character referred to is inserted through the opening 31 and the hook of the implement is engaged beneath the arm 30 whereupon the implement may be lifted to raise the arm 30. This action causes the 20 walls of the slot 29 to engage the pin 25 and thus swing the locking member inwardly from its position beneath the flange 12 whereupon the manhole cover may be pulled upwardly by the hooked implement and removed from position. The movement of the 25 locking element to operative and inoperative positions is limited by the pin 26 contacting with the shoulders 24 of the cut-away portions 23, the pin 26 serving the additional 30 function of pivotally supporting the operating member 27. Since the movement of the locking member is thus limited, it will be apparent that when this element reaches the locked position shown in Figure 2, the pin 25 35 will prevent further movement of the operating member, thus limiting the downward movement of the arm 30. Thus it will be apparent that the pin 25 and slot 29 serve as connecting means for operating the locking member upon actuation of the arm 30, and also serve as means for limiting the turning 40 movement of the member 27. When the cover is removed, the free end of the arm 30 will contact with the bottom of the cover thus permitting the latter to be removed by pulling upwardly on the hooked implement without injuring any of the parts of the device. The structure of the stationary latch including the arms 16 and pin 17, provides better 45 casting conditions and relieves shrinkage due to the cooling of the metal, thereby providing a stronger latch.

It is to be understood that the form of my invention herewith shown and described is 50 to be taken as a preferred example of the same, and that various changes in the shape, size, and arrangement of parts may be resorted to without departing from the spirit of the invention or the scope of the subjoined claims.

I claim:

1. A locking device for manhole covers comprising a pivoted locking member carried by the manhole cover, a pivot pin carried by said cover, an actuating member car-

ried by said pivot pin and adapted to move said locking member to operative and inoperative positions, said locking member being provided with a cutout portion through which said pivot pin is adapted to extend to limit the swinging movement of said locking member.

2. A locking device for manhole covers comprising a locking member movable to operative and inoperative positions, a pivot pin carried by said cover, an actuating member carried by said pivot pin and adapted to move said locking member to operative and inoperative positions, said locking member being provided with a cutout portion having shoulders formed at the ends thereof with which said pivot pin is adapted to contact to limit the movement of said locking member.

3. A locking device for manhole covers comprising an upstanding locking member pivotally connected at its lower end to the manhole cover and provided in its upper end with an arcuate cutout portion, a pivot pin carried by said manhole cover and extending through said cutout portion to contact with the ends thereof to limit the movement of said locking member, and an actuating member mounted on said pivot pin and movable to swing said locking member to operative and inoperative positions.

4. A locking device for manhole covers comprising a pair of depending arms carried by the manhole cover, a locking device pivotally mounted at its lower end between the lower ends of said arms and provided in its upper end with an arcuate cutout portion formed concentric to its pivot, a pivot pin extending between the upper portion of said arms and arranged in said cutout portion to engage the ends thereof and limit the swinging movement of said locking member, and an actuating member mounted on said pivot pin and movable to swing said locking member to operative and inoperative positions.

5. A locking device for manhole covers comprising a pair of depending arms carried by the manhole cover, a locking device pivotally mounted at its lower end between the lower ends of said arms and provided in its upper end with an arcuate cutout portion formed concentric to its pivot, a pivot pin extending between the upper portion of said arms and arranged in said cutout portion to engage the ends thereof and limit the swinging movement of said locking member, a pin carried by said locking member, and an actuating member mounted on said pivot pin and provided with a slot arranged substantially radially with respect to said pivot pin and receiving the pin carried by said locking member.

6. A locking device for manhole covers comprising a pair of depending arms carried by the manhole cover, a locking device pivotally mounted at its lower end be-

tween the lower ends of said arms and provided in its upper end with an arcuate cut-out portion formed concentric to its pivot, a pivot pin extending between the upper portion of said arms and arranged in said cut-out portion to engage the ends thereof and limit the swinging movement of said locking member, a pin carried by said locking member, and an actuating member mounted on said pivot pin and provided with a slot arranged substantially radially with respect to said pivot pin and receiving the pin carried by said locking member, said actuating member being provided at one side of the pivot thereof with a horizontally extending weight arm movable downwardly by gravity to normally maintain said locking member in operative position.

7. A locking device for manhole covers comprising a pair of spaced depending arms carried by the manhole cover, a locking device pivotally mounted at its lower end between the lower ends of said arms and including a pair of spaced upstanding arms each provided in its upper end with an arcuate slot concentric with the pivot of said locking member, a pin extending between the upper portions of said depending arms and arranged in said slots to contact with the ends thereof and limit the swinging movement of said locking device, a pin extending between the arms of said locking device above the pivot thereof, and an actuating member mounted on said pivot pin and having one end arranged between the arms of said locking member and provided with a slot receiving the pin mounted between the arms of said locking member, said actuating member being provided to one side of said pivot pin with a horizontally extending weight arm movable downwardly by gravity to normally urge said locking member to operative position.

8. A locking device for manhole covers comprising a pair of depending arms carried by the manhole cover adjacent one side

thereof and provided with outwardly extending lower ends, a pin connected between the lower ends of said arms, a pivoted locking member arranged beneath the opposite side of the manhole cover, a pivot pin carried by the cover, an actuating member carried by said pivot pin and adapted to move said locking member to operative and inoperative positions, said locking member being provided with a cutout portion through which said pivot pin is adapted to extend to limit the swinging movement of said locking member, the manhole cover being provided above said actuating member with an opening for the reception of an operating tool adapted to engage said actuating member.

9. The combination with a manhole frame having an open top and provided with an internal annular flange, and a cover adapted to be supported on said flange, of a pair of integral depending arms carried by the cover adjacent one side thereof and provided with oppositely extending lower ends, an integral pin connected between the lower ends of said arms and arranged beneath said annular flange, a pivoted locking member arranged beneath the opposite side of said cover, and having a portion adapted to engage beneath said annular flange, a pivot pin carried by said cover above said locking member, an actuating member carried by said pivot pin and adapted to move said locking member to operative and inoperative positions, said locking member being provided with a cutout portion through which said pivot pin is adapted to extend to limit the swinging movement of said locking member, the cover being provided above said actuating member with an opening for the reception of an operating tool adapted to engage said actuating member.

In testimony whereof I affix my signature.

CHALMERS S. BROWN.
